UNITED STATES PATENT OFFICE.

AUGUST F. W. VIEHWEGER, OF POUGHKEEPSIE, NEW YORK, ASSIGNOR TO VIEHWEGER LOCK COMPANY, INC., OF POUGHKEEPSIE, NEW YORK, A CORPORATION OF NEW YORK.

SHEET-METAL LOCK.

Application filed April 27, 1927. Serial No. 186,936.

The present invention relates to locks and particularly to door locks, and one object of the invention is to provide a lock substantially all the operating parts of which 5 are of a form adapted to be stamped out from sheet metal, thus conducing to economy of manufacture and ease of assembly.

Another object is to provide a lock in which substantially all the operating parts 10 are stamped out from sheet metal and the lock case or housing and cover thereof are stamped out.

A further object is to provide a lock the strikers or bolts of which are spring actuated to locking position and which when in locking position may be so retained or set 15 as to constitute a dead bolt lock.

A feature of the invention is the employment of a pair of lock arms pivoted at one 20 of their ends for diverging or converging movement relative to each other at their other or free ends, and having on their free ends strikers or bolts projectible for engagement with a suitable keeper by diverging 25 movement of the arms at their free ends and retractable for disengagement from said keeper by converging movement of the arms at their free ends.

Another feature of the invention is the 30 employment of a cage member in which the strikers on the free ends of said arms are received and by which they are guided and maintained in alinement during projection or retraction of the strikers for engagement 35 with or disengagement from the keeper by movement of said lock arms.

I attain these objects and such other objects as may later appear in the subjoined specification descriptive by way of example 40 of one of the possible embodiments of the invention and shown in the accompanying drawings forming part of the specification, it being understood that I may make modifications and variations of the invention 45 without departing from the spirit thereof or exceeding the scope of the appended claims.

In the drawings Fig. 1 is a plan of the lock, the cover of the housing being removed 50 and the strikers being projected for engagement with a suitable keeper, or in locking position, and retained or set in locking position.

Fig. 2 is a plan of the lock and similar to

Fig. 1, except that the strikers are shown 55 retracted for disengagement from a suitable keeper, or in unlocking position, and are retained or set in unlocking position.

Fig. 3 is a sectional view on the line 3—3 of Fig. 1.

Fig. 4 is a plan of the cover of the lock casing or housing viewed from the under side thereof.

Fig. 5 is a plan of the lock casing or housing formed by stamping from the sheet 65 metal blank shown in Fig. 7.

Fig. 6 is an end view of Fig. 5.

Fig. 7 is a view of the extended sheet metal blank for forming the case or receptacle portion of the housing by stamping the 70 blank, and

Fig. 8 is a fragmentary perspective view of the guiding and alining cage member.

Referring to Figs. 1, 2, and 3, the lock embodies the oblong case generally denoted 75 by C, having the side walls 10 and end walls 11 and 12, the side walls 10 for a portion of the length of the sides having at their free edges the flanges 13 provided with screw holes for securing the lock to a door 80 or other closure means. The side walls 10 adjacent to the end wall 12 have therein the openings 14, best seen in Fig. 7, and the bottom 15 of the case has the aperture 16 therethrough which receives the spindle 17 85 having the manipulating knob 18 thereon.

The base and box member 19 is disposed on the bottom 15 of the case and has near one end thereof the aperture 20 through which the spindle 17 passes, and has near 90 the other end of the member the upstanding transverse rib 21. The member 19 is provided for a portion of the length of its base with the side walls 22 which extend upwardly to near the top line of the side walls 95 10 of the case C. The side walls 22 are cut away longitudinally for a distance at one of their ends from the base line of the member 19 to about the middle longitudinal line of the side walls 22, the portions of these 100 walls remaining after thus cutting away being bent inwardly to form the end walls 23 spaced away at their bottom edges from the base of the member 19 and spaced away from each other at their ends, the side walls 22 and end walls 23 forming a box like portion 105 of the member 19; the member 19 at one of its ends is spaced away on the bottom 15

of the case C from the end wall 11 by engagement of the spindle 17 in the aperture 20 and at its opposite end abuts the end wall 12 of the case, longitudinal movement 5 of the member being thereby prevented. The member 19 is formed by stamping from a metal sheet, by stamping being meant here and elsewhere herein any well known manner of forming the member from a metal 10 sheet by pressing or bending the sheet.

Each of the lock arms 24 is of the shape shown in the drawings. The lock arms 24 are pivotally supported at one of their ends and located on opposite sides of the spindle 17, the lock arms extending on each side of the spindle 17 and being movable at their opposite or free ends divergently or convergently relative to each other. The lock arms 24 are spaced away at one of their ends from 20 the base of the member 19 by the studs 25 and are spaced away therefrom at their other ends by resting on the rib 21. Substantially one-half of each of the lock arms is located in the box like portion of the member 19 in a plane below the bottom edges of the end walls 23 and the other half of the lock arms is located in the open space of the case and passes under the end walls 23 and extends towards the end wall 12 of the case. 25

Each of the lock arms 24 is provided with a diagonal slot S open at the end of the slot adjacent to an end wall 23 of the member 19, the slots S converging relative to each other. The coil spring 26 is disposed around the spindle 17 and respective ends 30 of this spring are secured to the lock arms 24, the tendency of the spring 26 being to cause diverging movement of the lock arms at their free ends. Each lock arm 24 has secured on the surface of the free end thereof by a headed pin 24^a a striker or lock bolt 24^a, the lock arms 24 being formed by stamping from a metal sheet. 35

The slide plate retractor 28, when viewed as in Fig. 1, the lock arms 24 being in diverging position, has a rectangular main portion 29 substantially wholly contained within the confines of the box-like portion of the member 19, and a truncated cone shaped end portion 30 passing under the end walls 23 of the member 19 and extending outwardly from the box-like portion of this member, the converging sides of the end portion 30 being bent downwardly to form ears 31 on the under side of the end portion 30, the respective ears 31 engaging respective slots 8 of the lock arms 24. The retractor 28 has therethrough the aperture 32 through which the spindle 17 passes. The retractor 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 - head 52 of the bushing for movement with the bushing. The bushing 51 has thereon the outer head 53 bearing on the cover 49 and having therein the opening 54 adapted to receive the stem 55 for rotating the bushing when the stem 55 is actuated by a key operated lock, not shown, accessible from the outer side of the door or closure means. The cam member 48 is provided with ears 56 which severally engage the abutments 35 and 36 of the member 19 and which when the bushing 51 is moved by the stem 55 retractably move the retractor 28 whereby the lock arms 24 are convergently moved and the strikers 24^a are retracted to unlocking position, the cam member 49 being formed by stamping from a metal sheet.
- The slide plate retractor 28, Figs. 1, 2 and 3, is provided at its end adjacent to the end wall 11 of the case C with a bent end portion 57 with which the pin 58 of settable pin and slot means appurtenant to the bottom 15 of the case engages, the pin 58 when engaged with the inner side of the bent portions 57 retaining the strikers 24^a in retracted or unlocking position, the pin 58 when engaged with the outer side of the bent portion 57 retaining the strikers 24^a in projected or locking position and the lock then constituting a dead bolt lock.

The cover 49, Fig. 4, is formed by stamping from a metal sheet and is provided with the bolt hole 59, and with the aperture 50 before mentioned, and has at its ends the extensions 60 and 61. The cover is secured to the case C by the bolt 62 passing through the hole 63 in the bottom of the case and between the movable ends of the lock arms 24 and threaded into the bolt hole 59, the extensions 60 and 61 being received in the recesses 64 and 65 of the end walls 11 and 12 for positioning the cover on the case.

The blank, Fig. 7, for forming the case C by stamping is a metal sheet and includes the rectangular bottom section 15 having therethrough the aperture 16 and bolt hole 63, the side sections 10 on the bottom section 15 and defined therefrom on their inner sides by the parallel longitudinal bend lines 66 and free on portions of their outer sides and having longitudinally extending securing flange sections 13 on portions of their outer sides defined from the side sections by the bend lines 67 parallel to the bend lines 66, said side sections having free ends and striker openings 14 through the side sections adjacent to one of their free ends, and end sections 11 and 12 defined on their inner sides from the bottom section 15 by the parallel transverse bend lines 68 and free on their outer sides and ends, the end section 11 having in its free side the recess 64 and the end section 12 having in its free side the recess 65.

To form the case C from said blank the

side sections 10 are bent on the bend lines 66 to lie at right angles to the plane of the bottom section 15, the flange section 13 are bent outwardly from the side sections on the bend lines 67 to lie in a plane parallel to the plane of the bottom section, and the end sections 11 and 12 are bent on the bend lines 68 to lie at right angles to the bottom section 15.

What I claim and desire to protect by Letters Patent is:

1. In a lock, in combination, a pair of lock arms movable divergently to locking position and convergently to unlocking position, means for moving the lock arms divergently, a retractor embracing the said lock arms, said lock arms when moved divergently moving said retractor to projected position, said retractor when moved from projected position to retracted position moving said lock arms convergently, hand operated means for moving the retractor from projected position to retracted position, and means operated by an auxiliary lock for moving the retractor from projected position to retracted position.

2. In a lock, in combination, a pair of lock arms movable divergently to locking position and convergently to unlocking position and having strikers on their divergently or convergently movable ends, means for moving the lock arms divergently, a retractor embracing the lock arms, said lock arms when moved divergently moving said retractor to projected position, said retractor when moved from projected position to retracted position moving said lock arms convergently, means for moving said retractor from projected position to retracted position, and means for guiding and alining said strikers in their movement when the lock arms are moved divergently or convergently.

3. In a lock, in combination, a base member, lock arms on said member pivotally supported at one of their ends for diverging or converging movement at their opposite ends, said arms being movable divergently to locking position and convergently to unlocking position, means for moving the lock arms divergently, a retractor embracing the lock arms, said arms when moved divergently moving said retractor to projected position, said retractor when moved from projected position to retracted position moving said arms convergently, and means for moving said retractor from projected position to retracted position and thereby moving the lock arms convergently.

4. In a lock, in combination, a base member, lock arms on said member pivotally supported at one of their ends for diverging or converging movement at their opposite ends, said arms being movable divergently to locking position and convergently to un-

- locking position, means for moving the lock arms divergently, a retractor embracing the lock arms, said arms when moved divergently moving said retractor to projected position, said retractor when moved from projected position to retracted position moving said arms convergently, hand operated means for moving said retractor from projected position to retracted position and thereby moving the lock arms convergently.
- 10 5. In a lock, in combination, a base member, lock arms on said base member pivotally supported at one of their ends for diverging or converging movement at their opposite ends and having strikers on said opposite ends, said strikers being moved to locking position when said arms are moved divergently and moved to unlocking position when said arms are moved convergently, means for moving the lock arms divergently, a 20 retractor embracing the lock arms, said arms when moved divergently moving said retractor to projected position, said retractor when moved from projected position to retracted position moving said arms convergently, means for moving said retractor from projected position to retracted position and thereby moving the lock arms convergently, and means for guiding and alining said strikers when they are moved by diverging 30 or converging movement of the lock arms.
6. In a lock, in combination, a pair of lock arms movable divergently to locking position and convergently to unlocking position, a retractor embracing the lock arms, said arms when moved divergently moving said retractor to projected position, said retractor when moved from projected position to retracted position moving said arms convergently, and means for retaining the 40 retractor in projected position and thereby retaining said arms in locking position and for retaining the retractor in retracted position and thereby retaining said arms in unlocking position.
- 50 7. In a lock, in combination, a case, a pair of lock arms movable divergently to locking position and movable convergently to unlocking position, a retractor embracing the lock arms, said arms when moved divergently moving said retractor to projected position, said retractor when moved from projected position to retracted position moving said arms convergently, and means cooperating between said case and retractor for retaining the retractor in projected position and thereby retaining said arms in locking position and for retaining the retractor in retracted position and thereby retaining said arms in unlocking position.
- 55 8. In a lock, in combination, a base member, a pair of lock arms superimposed on said member and pivotally supported at one of their ends for diverging or converging movement at their opposite ends and having diagonal slots, the slot of one arm converging towards the slot of the other arm, said arms being movable divergently to locking position and convergently to unlocking position, means for moving said arms divergently, a retractor having abutment means on one face thereof and having dependent ears on the opposite face thereof, said ears engaging said slots, said arms when moved divergently moving said retractor to projected position, said retractor when moved from projected position to retracted position moving said arms convergently, and cam means engaging said abutment means for moving the retractor from projected position to retracted position and thereby moving said arms convergently.
9. In a lock, in combination, a base member, a pair of lock arms superimposed on said member and pivotally supported at one of their ends for diverging or converging movement at their opposite ends and having diagonal slots, the slots converging towards each other, said arms being movable divergently to locking position and convergently to unlocking position, means for moving said arms divergently, a retractor having abutment means on one face thereof and dependent ears on the opposite face thereof, said ears engaging said slots, said arms when moved divergently moving said retractor to projected position, said retractor when moved from projected position to retracted position moving said arms convergently, and cam means operated by an auxiliary lock and engaging said abutment means for moving the retractor from projected position to retracted position and thereby moving said arms convergently.
10. In a lock, in combination, a base member, a pair of lock arms superimposed on said member and pivotally supported at one of their ends for diverging or converging movement at their opposite ends and having strikers on said opposite ends movable to locking position by diverging movement of said arms and movable to unlocking position by converging movement of said arms, said arms having slots therein, means for moving said arms divergently, a retractor having abutment means on one face thereof and dependent ears on the opposite face thereof, said ears engaging said slots, said arms when moved divergently moving said retractor to projected position, said retractor when moved from projected position to retracted position moving said arms convergently.

- ingly, cam means engaging said abutment means for moving the retractor from projected position to retracted position and thereby moving said arms convergently, and 5 a cage for receiving said strikers and guiding and alining the strikers in their movements to locking or unlocking position when said arms are moved divergently or convergently.
- 10 11. In a lock of the character described, a member consisting of a rectangular base having at one end portion thereof stamped side walls and stamped end walls at one end of said side walls, said end walls being cut 15 away at their lower edges from the face of said base and thereby spaced away from the base at their lower edges, said end portion and side and end walls constituting a box like structure on said base, the other end 20 portion of said base extending in direction away from said structure in the longitudinal line of the base and being free of side and end walls and having a free end and an upstanding stamped transverse rib near its 25 free end.
12. In a lock of the character described, cooperating lock arms, said arms being of similar shape, each arm having an apertured end and a diagonal slot in one side of the 30 arm intermediately of the ends of the arm, the end of the arm opposite said apertured end being adapted for receiving a striker thereon, the slots of the arms converging towards each other when the arms are co- 35 operatively disposed.
13. In a lock of the character described, co-operating arms of similar stamped contour, each arm having a stamped aperture in one end of the arm and a stamped diagonal slot in one side of the arm intermediately of the ends of the arm, the end of the arm opposite said apertured end being adapted for securing a striker thereon, the 40 slots of the arms converging towards each other when the arms are co-operatively disposed.
- 45 14. In a lock of the character described, a cam member of stamped contour and having
- an arcuate main portion and a circular apertured portion for rotatably mounting the 50 member, said arcuate portion having at its ends stamped ears disposed at an angle to the plane of the arcuate portion and constituting cam faces.
15. In a lock, in combination, a casing having oppositely related openings in its side walls at one end of the casing, strikers projectible or retractable through said openings, and means disposed in said casing adjacent to said openings for receiving said strikers 60 and guiding and alining the strikers when they are projected or retracted through said openings.
16. In a lock of the character described, a cage having stamped parallel side walls free 65 at their ends, one of said side walls being of less height than the other, the top edges of the side walls lying in the same plane and being connected about midway of the length of the side walls by a stamped cross-piece. 70
17. A blank for forming a lock casing by bending the blank on the bend lines thereof, said blank being of sheet metal and including an oblong bottom section side wall sections 75 on the bottom section and defined therefrom along one of their sides by parallel longitudinal bend lines and free on their ends and for a portion of their other sides and having openings through the sections near one of their ends, said openings registering when 80 the side walls are in assembled bent relation, end wall sections on the bottom section and defined therefrom on one of their sides by parallel transverse bend lines and free on 85 their other side and ends, and securing flange sections on the side wall sections and defined therefrom on one of their sides for a portion of the length of the side wall sections by longitudinal bend lines parallel to the first mentioned bend lines, said flange 90 sections being free on their other sides and at their ends.

Signed at Poughkeepsie, in the county of Dutchess and State of New York, this 23rd day of April, A. D. 1927.

AUGUST F. W. VIEHWEGER.
